(57) **CLAIM**

I claim the ornamental design for a fishing rod rest, as shown and described.

DESCRIPTION

FIG. 1 is a front perspective view showing my design;

FIG. 2 is a top view thereof;

FIG. 3 is a bottom view thereof;

FIG. 4 is a side view thereof;

FIG. 5 is a front view thereof;

FIG. 6 is a rear view thereof; and,

FIG. 7 is a perspective view showing the design in an illustrative environment.

The broken lines depict environmental structure and form no part of the claimed design.
